VALVE MECHANISM

Arthur J. Penick and Kirby T. Penick,
Houston, Tex.Application November 25, 1929
Serial No. 409,541

1 Claim. (Cl. 251—144)

This invention relates to new and useful improvements in valve mechanism.

One object of the invention is to provide a valve mechanism of the character described specially adapted for use in pumps such as slush pumps for handling gritty material and embodies a novel type of valve as well as a novel type of seat with which the valve cooperates.

Another object of the invention is to provide in a valve mechanism a seat having a ring thereon formed of rubber or similar yieldable material against which the valve is adapted to seat and which has a yieldable margin which will conform to and fit closely against the opposing face of the valve so as to at all times form there-with a fluid tight joint to prevent leakage.

Another object of the invention is to provide in a mechanism of the character described, a valve having a detachable ring arranged to cooperate with the valve seat and which may be readily removed and replaced when it becomes worn out.

With the above and other objects in view the invention has particular relation to certain novel features of construction, operation and arrangement of parts, an example of which is given in this specification and illustrated in the accompanying drawing wherein:

Figure 1 shows a side view of the mechanism, partly in section as mounted in a slush pump.

Figure 2 shows a vertical sectional view of a modified form of the valve seat and

Figure 3 shows a fragmentary vertical sectional view of another form thereof.

Referring now more particularly to the drawing, wherein like numerals designate similar parts in each of the figures the numeral 1 designates a slush pump as a whole, which has a transverse horizontal partition 2 therein which separates the intake chamber beneath the valve mechanism from the discharge chamber 3 above said valve mechanism. In the partition 2 there is driven, or otherwise secured, a valve seat 4 whose upper end is flared. This seat is formed of rigid material and around its upper end there is a ring 5 formed of rubber or some other yieldable material having the flared face 6 which has a slightly less flare than the flare of the seat proper. The upper end of the valve seat 4 is reduced forming the annular shoulder 7 on which the ring 5 is seated. The ring 5 surrounds said reduced portion and has an inside annular rib 8 at its lower end which fits into a corresponding groove 9, in the reduced portion of said seat. The ring 5 may be expanded and fitted over the

reduced upper end of the seat 4 and then released to seat the rib 8 in the groove 9 and the ring will thereby be held in position.

In the form shown in Figure 2 the ring 5a is formed and mounted in substantially the same manner as shown in Figure 1. In the form shown in Figure 2 there is a non-expansible band 10 around the lower portion of the ring 5a whose upper edge is substantially flush with the upper edge of the flared portion of the seat 4. In the form shown in Figure 3, there is a band 10' surrounding the yieldable ring 5b which is formed integrally with the seat 4 and whose upper edge is substantially flush with the upper edge of the flared portion of said seat. It will thus be observed that the upper edge 11 of the yieldable seat 5, 5a or 5b is free to yield under the action of the valve 12 there against and wear and friction of the valve against the seat will not be so severe as would be the case were said yieldable ring backed by a nonyielding backing. The ring 5, 5a, 5b will therefore be free to conform to the contour of the valve 12 and should any clogging material be caught between the ring and valve, said ring will have a certain amount of resiliency to enable the ring to conform to the irregularity and to form a close fit with the valve. There is a ring 13, secured to the under side of the valve 12 and having the tapering face 14 to conform to the contour of the valve seat, and to cooperate therewith. This ring is seated in a groove 15 in the underside of the valve proper and is secured therein by suitable bolts, as 16.

In the seat 4, beneath the valve, there is a spider 17 having the central bearing 18 through which the depending stem 19 works, and up-standing from the valve there is a stem 20 which works in the guide 21, located in the pump above said valve. If desired, a coil spring 22 may be placed around the stem 20 and interposed between said guide and valve to assure the seating of the valve. This spring however is not indispensable as ordinarily the valve will close under the influence of gravity.

As stated the flare or pitch of the ring 5, 5a, 5b is somewhat less than the flare, or pitch, of the upper end of the seat as shown in Figures 2 and 3. When the valve seats against said ring it will first contact against the upper edge or apex 11 and cause said edge to yield outwardly before the valve seats fully against the face 6. This will give a better contact against the valve and will also cause the ring to wear longer.

The drawing and description disclose what is now considered to be the preferred form of the

invention by way of illustration only, while the broad principle of the invention will be defined by the appended claim.

What we claim is:—

- 5 A valve mechanism comprising a reciprocable valve having an annular beveled face, an annular valve seat having an outwardly flared annular face opposite, and adapted to cooperate with, said valve face, a ring of resilient material around and counter sunk into the valve seat and having an outwardly flared face which terminates in an annular lip which lies in a plane which is elevated beyond the plane of the seat face whereby, upon closing movement of the valve, the valve

face will contact with said lip in advance of the complete seating of the valve on said seat, said seat having an external annular groove and said resilient ring having an internal annular rib which seats in said groove and also having an external annular groove and a band around, and counter sunk into, the base portion of said ring which secures the ring in place but permits the expansion of the lip portion of the ring, said band having an inside annular rib which seats in the groove of said ring.
